UNITED STATES PATENT OFFICE

LOU A. MORRIS, OF AURORA, NEBRASKA

MEANS FOR MAKING POTATO CHIPS

Application filed December 11, 1928. Serial No. 325,288.

This invention embodies a new method, and complemental means for making a distinctively different type of potato chip in contrast to the form of chips ordinarily made and marketed.

The principal novelty is predicated upon the characteristic method followed in the slicing of the raw potato preparatory to frying.

10 A subordinate feature of novelty is, however, based upon the physical means, which is utilized in conjunction with the method for permitting accomplishment of the task in a satisfactory and highly economical and desirable manner.

15 The procedure embodied in the new method of making, as well as the mechanical details incorporated in the device used will become more readily apparent from the following description and drawings.

In the drawings:

Figure 1 is a top plan view of the preferred form of device, utilized in carrying out the invention.

20 Figure 2 is a side or edge elevational view of Figure 1.

Figure 3 is an enlarged fragmentary sectional view, taken approximately upon the plane of the line 3—3 of Figure 1.

25 Figure 4 is a cross sectional view, taken approximately upon the plane of the line 4—4 of Figure 3.

Figure 5 is a top plan view of one of the species of chips made in accordance with the present invention.

30 Figure 6 is an exaggerated view taken approximately upon the plane of the line 6—6 of Figure 5.

It is logical to first describe the mechanical contrivance or preferred device, which is employed in carrying the invention into actual effect. This device, as shown in Figures 1 and 2 is principally made up of a sectional base of a portable design, one section of which is designated by the reference character 7, and the complemental section of which is designated by the character 8. Associated with these two sections is the slicing elements 9.

35 The part 7 comprises a paddle shaped

rest or base 10, having an upper flat face against which the peeled potato is placed in an upright position. This part includes a manipulating handle 11. Disposed in a substantially horizontal plane with the base 10 is a block-like element 12, functioning as a stop and reinforcing member. This is disposed in spaced relation to an adjacent end of the complemental section 10, and the forward edge thereof is bevelled rearwardly and downwardly as at 13 to provide a chute 14, between the sections, and the slices of potato pass down through the chute into a suitable receiving pan or receptacle. The slicing plate comprises a longitudinally corrugated plate 15, the major portion of which is fastened to the block 12, in such a way that the forward end extends beyond the bevelled edge 13, and bridges the space or chute 14. This forward end is provided with depending legs 16, which as shown in Figure 4 are provided with slots 17, adjustably connected with the adjacent end of the base section 10, through the medium of screws or the like 18. This allows the two elements 12 and 15 to be adjusted as a unit with respect to the parts 10. Thus the forward edge of the plate 15 operates as a cutting edge 19, and this is arranged for disposition in spaced relation to the flat top 70 of the section 10.

It follows that I provide a sectional base, wherein the sections are spaced apart to provide a tooth, and wherein one section is relatively adjustable with respect to the other section and carries the slicing plate, whereby to permit the thickness of the slices to be regulated.

In the ordinary method of slicing potatoes for making chips, the raw peeled potato is sliced squarely across. The result is that the slices become nested together and mold and spoil and soon become soggy. In accordance with the improved method, however, the potato is placed end down against the top of the section 10 of the base and drawn against the cutting edge 19 of the slicing plate 15. With each new slice, the potato is turned one-quarter of a circle. In this manner, the slice is permitted to drop 100

down through the chute into the receiving receptacle. The edges of the sliced product are all bevelled by this method of slicing, and the hot grease pours through the apertures in the slices and cooks the entire product thoroughly. The bevelled edges are cooked harder and thus return a crisp and firm condition, and the product remains in a superior condition for days. With the grease boiling through the apertures, every portion of the slice is thoroughly cooked.

The corrugated slicer plate must be adjusted to the proper spaced elevation above the top of the section 10 of the base. If the slicer is raised too high, the slice of the potato will be too thick and there will be no holes in the slice. The slice would have grooves without holes. By adjusting the slicer and making the proper quarter turn each time the potato is moved against the cutting edge, holes are made in the slice, and the product has the appearance of a grooved waffle with holes clear through it. The product is attractive to the eye, remains crisp, firm and sweet much longer than the ordinary chip. Moreover, the chips when packaged do not become nested together.

A careful consideration of the description in conjunction with the drawings will enable the reader to obtain a clear understanding of the construction of the slicing device, the method of manufacture, and the character of the product made. Incidentally, by reference to Figures 5 and 6 of the drawings, the new product will be seen, wherein it is designated generally by the reference character 20, and wherein it will be observed that it is corrugated and formed with a multiplicity of irregularly arranged openings or apertures 21. Of course, these chips will vary slightly in design, but the general principles will be present in each chip if the method described is properly followed.

45 Minor changes in shape, procedure, and materials may be resorted to, in actual practice, if desired.

I claim:

50 A potato slicer comprising a paddle shaped rest having a handle and presenting an upper flat face against which the potato is adapted to be supported; a longitudinally corrugated slicing plate having depending legs at one end, provided with slots, said leg adapted to rest flat against the forward edge of the said paddle shaped rest, fastening means carried by the said saddle rest and engaging the said slotted legs of the said slicing plate, for adjustably connecting together the said saddle rest and slicing plate, the latter being normally positioned with its cutting edge slightly spaced above the plane of the said flat face of the rest, whereby the slices are adapted to pass 55 under the slicing plate, and an abutment

member secured to the under side of the slicing plate and presenting a rearwardly and downwardly inclined edge against which the said slices are adapted to abut and by which they are deflected downwardly.

In testimony whereof I affix my signature.

LOU A. MORRIS.
